WEFT REPLENISHING APPARATUS FOR
WEAVING LOOMS

Henry James Cooper, Stockport, England

Application February 28, 1951, Serial No. 213,247
In Great Britain March 15, 1950

18 Claims. (Cl. 139—224)

1

This invention relates to weft replenishing apparatus for weaving looms wherein shuttles travel circularly in a unidirection.

According to the said invention a weft replenishing apparatus for weaving looms wherein shuttles travel circularly in a unidirection has weft coilers each of which is driven along a circular path and during its movement comes into register with and, whilst in register, travels at the same speed as a shuttle, coils of weft being slipped from the coiler and received by the shuttle whilst the coiler and shuttle are in motion.

Where the loom operates with a radial warp, the axis of the circular path of the coilers preferably is radial to the axis or an extension of the axis of the circular path of the shuttles and each coiler at the moment of registration with a shuttle is immediately above a weft carrier provided on the shuttle, whereby the weft coils can be slipped downwards on to the weft carrier whilst the coiler and shuttle are travelling along their paths.

The weft carrier and coiler are preferably made to be engagement one partly within the other at the moment that the weft coils are slipped on to the weft carrier, to maintain full control of the coils during the whole period of the slipping operation.

A coiler rotating mechanism is provided for rotating each coiler whilst moving along its circular path before it arrives in register with a shuttle, in order to wind coils of weft on to itself for replenishing a shuttle with weft.

A coiler decelerating, stopping and accelerating mechanism is provided preferably for varying the speed and causing stoppage of the coiler along its circular path in order to facilitate the feeding of weft thereto, and if necessary, to give it a greater speed than a rotor driving it during the period of registration with a shuttle.

A weft gripping device is preferably provided for each coiler for gripping the leading end of a supply of weft preparatory to the coiler coiling some of the supply on to itself.

A weft presenting, guiding and holding mechanism is preferably provided for presenting the leading ends of supplies of weft to the coilers, guiding the weft as it is coiled on the coilers, and holding each weft at a point remote from its leading end until it has been woven into the warp.

The weft presenting, guiding and holding mechanism may have series of devices for presenting to each coiler any weft of different weft supplies and guiding and holding the presented weft until a portion thereof has been woven into the warp.

A feed mechanism may also be provided which takes the leading end of the presented weft from the presenting, guiding and holding mechanism

2

and feeds it to a gripping device provided on the coiler.

Each weft coiler may have an annular row of prongs on which the weft coils are wound and a pusher which operates to rotate the row of prongs and to push the coils along until they have slipped off the row of prongs in order to feed them to the carrier on the shuttle.

The prongs may be adjustable to change the diameter of the annular row of prongs.

The annular rows of prongs may be made rotatable about its own axis by the provision of a sleeve which is rotated by means of a gear wheel meshing constantly with an annular row of stationary teeth and can, by the action of a stationary cam, be connected to the pusher which is slidable relative to the annular row of prongs and adapted to rotate it about its own axis.

A coupling part may be provided on the pusher to effect a driving connection between the sleeve and the pusher when in operative position and lock the pusher against rotation when displaced from its operative position.

The coiler may have gripper jaws adapted to grip the leading end of a weft supply, one gripper jaw being on a spring loaded part associated with the annular row of prongs and the other jaw on the pusher to grip the yarn between them and maintain their grip whilst the pusher performs a portion of its pushing movement, and lose their grip by separation during the last stage of the said pushing movement.

The displacement of the pusher by the stationary cam to disconnect the drive thereof from the sleeve may be effected through levers, whilst a spring or cam may return the pusher.

Stationary cams are provided which act indirectly on each coiler so as to cause each of its journeys round its circular path to be temporarily stopped once whilst the coupling is shifted into the driving position, and temporarily stopped a second time whilst the coupling is shifted into the non-driving position prior to the transfer of the weft yarn coils to the shuttle.

The cams which effect temporary stoppage of the coiler along its stationary path and initiate the coiling rotation of the coiler may be adjustable to enable the length of weft wound on by the coiler to be varied.

In order that the said invention may be fully understood and more readily carried into practice, the accompanying drawing illustrate diagrammatically a constructional example. In the drawings—

Figure 1 is a plan view indicating the disposition of the replenishing mechanism relative to other parts of the loom.

Figure 2 is a rear elevation of parts of the said mechanism.

Figure 3 is a fragmentary side view, partly in

section taken on part of line 3—3 of Figure 2, of parts of the said mechanism.

Figure 4 is a fragmentary plan view of parts of the said mechanism.

Figure 5 is a fragmentary rear view of a part of the said mechanism regarded in the direction of the arrow 134 of Figure 3, parts of the figure being in section and a part which is shown in section being on a line corresponding with line 5—5 of Figure 6.

Figure 6 is a side view in section of Figure 5. Figures 5 and 6 are both drawn to a larger scale than Figures 1 to 4.

Figure 7 is a detached side view in section taken on line 7—7 of Figure 8.

Figure 8 is a fragmentary rear elevation illustrating a detail. Figures 7 and 8 are drawn to a larger scale than Figures 1 to 4.

Figure 9 is a fragmentary side view partly in section taken on a line corresponding to line 9—9 of Figure 10 and

Figure 10 is a plan view in section taken on line 10—10 of Figure 9.

Figure 11 is a fragmentary side view in section and

Figure 12 is a plan view of another detail which can be seen in side view, but drawn to a smaller scale and not in section, in Figure 3. Figures 9 to 12 are drawn to a larger scale than Figures 1 to 4, and

Figure 13 is a rear view in section showing another detail which can be seen in side view but in section and drawn to a smaller scale in Figure 3.

Referring to the drawings, in the construction shown therein, as applied by way of example to a loom wherein shuttles 1 move round a circular course through a radial warp having a gap 2 which exposes each shuttle 1 once during each revolution, a stationary stand 3 is provided on the loom at the gap 2 and has rotatably mounted in it a main shaft 4 which projects from the stand 3 across the course of the shuttles 1 at a distance above the same and is radial to the axis 5 of the said course. The main shaft 4 is above the gap 2 and the course of the circular shuttles 1 and extends through a stationary part 6 of the stand 3 in which it is journaled. The main shaft 4 has a main disc 7 secured to it and therefore rotated by it. Rocker shafts 8, for example ten, are rotatably mounted on the main disc 7 in a circular row with their axes parallel with the axis of the main shaft 4 and spaced uniform distances apart around the main disc 7. A rocker arm 9 is fixed on each rocker shaft 8 at one side of the main disc 7 and has two studs provided with two rollers 10 and 11 respectively. Each roller 10 is acted on by a stationary inner speed control cam 12 and each roller 11 by a stationary outer speed control cam 13. A rocker arm 14 is fixed on each rocker shaft 8 at the other side of the main disc 7.

Main arms 15 whose number equals that of the rocker shafts 8 are mounted side by side on the main shaft 4 at the last named side of the disc 7 so as to be free to rotate independently of the main shaft 4 and are bent where necessary so that their ends are all in a common plane which is at right angles to the axis of the main shaft 4. Each main arm 15 has a coiler 16 provided on it. For the sake of clarity the coilers 16 and their associated parts are shown only conventionally in Figures 1 and 2, and in some detail in Figures 5 and 6. The main arms 15 are severally connected by pivotal links 17 to the rocker

arms 14 so that actuation of each rocker arm 14 by the stationary inner and outer cams 12 and 13 acting through the rollers 10 and 11 causes angular displacement of each main arm 15 and its coiler 16 relative to the main disc 7.

The main shaft 4 is connected by gearing (not shown) to the loom drive so that, assuming the shuttles 1 to travel in anticlockwise direction, the main shaft 4, regarded in the direction of the arrow 18, Figure 1, rotates also in anticlockwise direction, and therefore the coilers 16 and main arms 15 are driven through the main disc 7, rocker shafts 8, rocker arms 14 and pivotal links 17 also in anticlockwise direction when the main arms 15 are in motion. The coilers 16 therefore revolve about the axis of the main shaft 4 in the direction of the arrow 19, Figure 2, whilst the shuttles 1 travel in the direction of the arrow 20.

Each coiler 16 has a sleeve 21, Figure 6, which is rotatably mounted and the axis of which is in the said plane. The projecting end of the sleeve 21 has a toothed bevel wheel 22 which is in constant mesh with a ring having a circular row of bevel crown teeth 23 and provided on the stationary stand 3. Revolution of the coilers 16 about the axis of the main shaft 4 therefore causes the sleeves 21 to be rotated about their own axes by the action of the stationary teeth 23 on the toothed bevel wheels 22.

Each sleeve 21 has an annular external row of coupling lugs 24. A hollow shaft 25 extends into the sleeve 21 which is rotatable independently of the shaft 25. A rod 26 is slidable in the hollow shaft 25 and has a bell 27 which is provided with an annular internal row of coupling lugs 28 adapted to cooperate with the lugs 24. The bell 27 also has an annular external row of locking lugs 29 adapted to cooperate with an annular internal row of locking lugs 30 provided on the coiler 16. The hollow shaft 25 projects outwardly beyond the sleeve 21 and has at its outer end a circular flange 31 on which there is a ring 32 which can slide on but must rotate with the flange 31. The ring has spaced jaws 33 and is acted on by compression springs 34. The flange 31 has a skirt 35 having an annular row of spaced prongs 36. Jaws 33 slide in the gaps between the prongs 36 and register with the jaws 33. The jaws 33 are provided on a dished disc 38 which is connected to the shaft 26. The shaft 26 is connected to a head 39 which has a swivel piece 40 connected by a pivotal link 41 to a lever 42 pivotally connected at 43 to the main arm 15. It is on the row of prongs 36 that the weft is coiled by rotation of the flange 31 and therefore the skirt 35.

The rod 26, disc 38 and jaws 37 form a driving connection between the bell 27 and the row of prongs 36. In the shown axial position of the bell 27, the lugs 29 thereof engage with the lugs 30 which, therefore, lock the bell 27, rod 26, disc 38, jaws 37, row of prongs 36, flange 31 and hollow shaft 25 against rotation about their own axes, notwithstanding the rotation of the sleeve 21 and its lugs 24 by the rolling of the wheel 22 along the row of teeth 23 as the main arm rotates about the axis of the main shaft 4. The drawings show the coiler coupling parts in the uncoupled position and therefore rotation of the row of prongs 36 interrupted. When the bell 27 is displaced in axial direction into a position where its lugs 29 are disengaged from the locking lugs 30 and its lugs 28 are engaged with the lugs 24, the bell 27 and therefore the row of prongs 36 are in a state

of driven connection with the driven sleeve 21 and rotation of the row of prongs about its own axis is taking place.

During each revolution of the row of prongs 36 around the axis of the main shaft 4, rotation of the row of prongs 36 about its own axis is interrupted for a period during which the weft coiled on to the row of prongs 36 by the said rotation can be slid off the row of prongs 36 so that the coiled weft arrives on one of the shuttles 1. The interruption of rotation of the row of prongs 36 about its own axis which endures whilst the coils are slid thereoff is initiated by a stationary uncoupling cam 44, see particularly Figures 7 and 8, associated with the stand 3 and actuating a slide 45 through rollers 46 on the slide 45 which is slideable inwards and outwards on the main disc 7. Each slide 45 has a short rib 47, see particularly Figure 6, which acts on a slide 48 through rollers 49 provided on the slide 48. The interposition of the slide 45 with its short rib 47 ensures a prolonged actuation and control of the slide 48 by the short rib when the main arm 15 is stationary relative to the cam 44, but the main disc 7 is in rotation relative to the main arm 15 as will hereinafter more clearly appear. The slide 48 is connected by a pivotal link 50 to the lever 42 and therefore controls the axial position of the bell 27 and the jaws 37 under the actions of the cam 44 and short rib 47. Prior to the start of coiling of weft on to the row of prongs 36, the cam 44 holds the slide 45 and therefore the slide 48 in a position where the link 50 holds the row of prongs 36 against rotation about its own axis and the jaws 37 in the out-thrust position shown in Figures 5 and 6. To commence coiling of weft its leading end is brought between the row of jaws 33 and the row of jaws 37 by a mechanism and in a manner hereinafter described so that it can be gripped between any one conveniently situated jaw 33 and its registering jaw 37. After the end has been gripped rotation of the row of prongs 36 can be commenced in order to wind the desired length of weft thereon. The said end is gripped by closing the registering jaw 37 on to its fellow jaw 33. The closing is effected whilst the coiler 16 is momentarily not rotating about the axis of the main shaft 4. The momentary non-rotation is produced by cam 13 rocking the respective arm 9 inwards and thereby rotating the respective main arm 15 rearwards relative to the forwardly rotating main disc 7. Whilst the main arm 15 is stationary, the rollers 46 of the slide 45 which is on the rotating main disc 7 are acted on by the stationary cam 44 so as to cause the slide 45 to move a short distance inwards and thereby also cause the slide 48 on the momentarily stationary main arm 15 to move inwards and by its action through the link 50, lever 42, link 41, swivel piece 40, head 39, rod 26 and disc 38 to raise the jaws 37 until one of them has forced the weft end against the registering jaw 33 and the weft end is gripped between the two jaws. This stoppage of the main arm 15 is caused always at the same point at each revolution and is due to the lift 51, Figure 8, of the cam 13.

The inward movement of the jaws 37 ceases before the lugs 29 become disengaged from the lugs 30 and therefore the bell 27 remains locked against unwanted rotation of the row of prongs 36 until it is desired to start coiling at a moment which will give exactly the required or desired length of coiled weft, for transfer to a shuttle 1. The coiling of the weft whose end is gripped between a jaw 33 and a jaw 37 is initiated by the

cam 44 after the main arm 15 has been stopped temporarily by the action of the lift 52 of the cam 13 acting on the arm 9. During this second stoppage of the arm and therefore the coiler, the continued movement of the main disc 7 carries the rollers 46 along the cam 44 and the lift 53 causes the slide 45 to move a further stage inwards. This movement is transferred via the slide 48 to the bell 27 which moves sufficiently to disengage its lugs 29 from the lugs 30 and engage its lugs 28 with the lugs 24 of the sleeve 21. Because, notwithstanding the continuous rotation of the main disc 7, the main arm 15 is momentarily stopped, the wheel 22 of the coiler of the said main arm does not rotate and therefore the disengagement of the lugs 29 and 30 and engagement of the lugs 24 and 28 takes place whilst none of those parts is in rotation and therefore quietly, with ease and without jarring. The jaws 37 are moved inwards a further stage by the described motion. The movement of the jaws 37 is not obstructed by the jaws 33 because the ring which carries the jaws 33 is pushed inwards against the action of the springs 34 whilst the jaws maintain their grip on the weft end. When the main arm 15 resumes its rotation, the wheel 22 rolls on the teeth 23 and therefore the row of prongs 36 is rotated about its own axis until a fall in the cam 44 operates through the slides 45 and 48 to return them outwards to their initial positions shown in Figure 6. When the jaws 37 are in their innermost position they leave a substantial portion of the prongs 36 exposed beyond the outer side of the said jaws. A stationary guide rail 54, Figures 2 and 3, guides the weft on to the said exposed portion and the weft is therefore wound into coils on the said portion in preparation for transference to a shuttle 1. The transference occurs after the required or desired length of weft has been coiled on the coiler and takes place as follows: Each empty shuttle emerges from the warp and travels into the gap 2, where, due to rotation of the main arms 15, it is met by one of the coilers 16 carrying on its row of prongs 36 coils of weft. The coiler and shuttle meet at the same speed and there is a moment whilst the coiler is exactly over the shuttle although both are travelling along their respective paths. The transfer of weft coils from the prongs 36 to the shuttle occurs at the said moment. The shuttle 1 has a weft bobbin 55 or post. This is shown in Figures 2 and 5 in momentary register with a coiler 16 and engaging loosely the dished disc 38 from below so that there is an overlap between the row of prongs 36 and the bobbin 55 or post which ensures that control of the coils shall not be lost during the transfer which takes place at and about the time that the coiler is travelling along the lowermost part of its path. Before the coiler reaches this point a fall on the cam 44 acts on the slides 45 and 48 to restore the jaws 37 to the hereinbefore described intermediate position in which they grip the weft end but do not displace the ring 32 and in which the drive of the row of prongs 36 is interrupted at the lugs 24 whilst the said row of prongs 36 is held against accidental rotation by engagement of the lugs 29 with the lugs 30. The intermediate position is reached after the required or desired amount of weft has been coiled on the prongs 36 and before the coiler and shuttle arrive in mutual registration. A further or continued fall in the cam 44 which moves the slides 45 and 48 still further to effect movement of the jaws 37 outwards, is effected so that they arrive in the shown position

at the moment of the said registration. This outward movement of the jaws 37 causes the said jaws to sweep the weft coils outwards or downwards completely off the row of prongs 36 so that they fall from the coiler on to the bobbin 55 or post before the coiler and shuttle are separated by their continuing motion along their different paths.

The stoppage of the main arm 15 by means of the cam 13 is effected without interrupting the rotation of the rotary main disc 7, by causing the rocker arm 9 to rock inwards and by its action through the rocker shaft 8, arm 14 and link 17 to cause the main arm 15 to revolve about the axis of the main shaft 4 in reverse direction to the direction of rotation of the main disc 7 but at the same speed as the main disc 7. These movements at the same speed but in reverse direction cancel each other out and the main arm 15 therefore ceases to revolve round the axis of the main shaft 4 and the wheel 22 therefore ceases to roll on the ring of stationary crown bevel teeth 23 and the sleeve 21 consequently ceases momentarily to be rotated about its own axis. The cam 12 may operate in the reverse manner to accelerate the motion of the main arm 15 so that it travels at its fastest speed whilst the transfer of coils takes place, and at a slower speed or speeds at other times, which is advantageous in that the performance of the other operations in preparation for the transfer takes place relatively more leisurely and therefore with increased certainty of result. After the operation of disengaging of the bell 27 from the lugs 24 and engaging of the bell 27 with the lugs 30 has been effected, the rocker arm 9 comes under the action of a lift on the inner speed control cam 12 which rocks it outwards and thereby rotates the main arm 15 relative to the main disc 7 in the same direction in which the main disc 7 is rotating and the speed of rotation of the main arm 15 about the axis of the main shaft 4 is therefore at the moment greater than the speed of rotation of the main disc. At that moment the linear speed of the row of prongs 36 is equal to the linear speed of the shuttle and it is at that moment that registration of the row of prongs 36 with the shuttle occurs. By this acceleration of the speed of revolution to a speed greater than that of the main disc and therefore the main shaft the uniform and uninterrupted speed of the main disc and main shaft can be slower than otherwise would be necessary to obtain an equal speed of the row of prongs and the shuttle at the moment of discharge of the weft thread from the prongs, which is advantageous to the efficient operation of the weft replenishing mechanism.

It is impossible for the coils to slip accidentally between the outer ends of the prongs 36 and the bobbin 55 or post or become twisted when slid off the prongs 36. As the jaws 37 push the coils to the ends of the prongs 36, they leave the jaws 33 and therefore they release the weft end so that it is transferred with the coils to the bobbin 55 or post on the shuttle.

Following the transfer of the charge of weft coils from the prongs 36 to the shuttle, which leaves the row of prongs 36 empty of weft thread, a fresh charge of weft coils is coiled thereon ready for transfer in its turn. As a preliminary to coiling each coiler is presented with the leading end of a weft supply by the following mechanism:

Each coiler 16 has a hollow feed arm 56 on a shaft 57, see Figures 5 and 6, journaled in lugs 58 so as to be free to rotate therein. To swing the arm 56 from the giving position shown in full

lines in these figures into the taking position shown in dot-and-dash lines and back again into the giving position, the shaft 57 has a spur wheel 59 acted on by a spur rack 60 which is provided on a spring-loaded rod 61 slidably mounted in the side of the coiler 16 and therefore rotating therewith round the axis of the main shaft 4. The end of the rod 61 is exposed to the action of a stationary annular cam 62 provided on the stand 3 and having a nose 63, Figure 8 which acts, as the main arm 15 revolves, to displace the rod axially against its spring load and thereby rotate the wheel to swing the arm 56 into the taking position where it takes the leading end of a weft supply held out to it at a pick-up station 64, Figures 1 to 3. To enable the arm 56 to take the presented leading weft end, it has a jaw 65 which cooperates with a pivotal jaw 66 pivoted at 67 and connected pivotally at 68 to a rod 69 which is slidable axially in the feed arm and is bent at 70 to clear the shaft 57 and has an end 71 on which a relatively stationary cam 72 operates to open the pivotal jaw 66 as the arm arrives in the taking position. There is also a relatively stationary cam 73 which again opens the jaw 66 as the arm 56 arrives in the giving position. A tension spring 74 connected to the arms 56 and 75 at the rod 69 by a lug 76 on the rod 69 closes the jaw 66 and keeps it closed when the cams 72 and 73 are not displacing the rod 69. The lug 76 projects through a slot 77 in the arm 56. A lateral prop 78 is provided on the arm 56 and has a notch 79 which, as the arm 56 swings from the taking position into the giving position, catches the weft end, and when the arm 56 has nearly reached the giving position cooperates with the jaws 65 and 66 to hold the weft extended between a jaw 33 and a jaw 37 in a position where the jaws 33 and 37 cannot fail to grip it. On the instant after the weft has been gripped by the jaws 33 and 37, the rod arrives under the action of the cam 73, which by opening the jaw 66 releases the weft from the jaws 65 and 66. Immediately thereupon a rise 134 provided on the cam 62 operates on the rod 61 to rotate the shaft 57 sufficiently to rock the arm 56 into a position where its jaw and prop parts are out of the path of rotation of the jaws 33 and 37 and thereby leave the jaws 33 and 37 free to be rotated.

To present at the feed station 64 a leading end of weft to the jaws 65 and 66 of each coiler 16 in turn once during each revolution of each coiler, there is a plurality of vertical slides, preferably more than there are coilers, for example 12 slides. These are indicated by reference numerals 80, 81, 82, 83, 84, 85, 86, 87, 88, 89, 90 and 91 respectively, see Figure 4, and are guided separately from each other by guide wheels, of which some are shown and marked 92 in Figure 3. The said slides are connected by pivotal links 93 separately to twelve levers 94 each of which is separately pivoted as at 95 and separately connected by a universal joint to a rod 96. Figure 3 shows 4 of these rods. Each rod 96 (Figure 13) is connected by a universal joint to a separate lever 97 fulcrummed at 98 and having a roller 99 which is acted on by a separate cam 100 to lift the slides 80 to 91 up and down separately. The cams 100 are connected together in angularly staggered positions and are rotated synchronously at a slower speed than the main shaft 4 by means of a compound spur wheel 101 meshing with a spur wheel 102 on the shaft 4 and with a spur wheel 103 connected to the cams and rotatably mounted on the

stand 3. The cams 100 cause every slide to perform the same rising and falling motions, but due to the angular staggering of the cams, the slides follow one another.

The guide wheels 92 are provided on an upper and a lower bracket 104 carried by a stationary post 105. Each slide 80 to 91 extends below the lower bracket 104 and has fixed to its lower end a foot 106, Figure 3. Each foot has suspended from it by two pivotal links 107 a pick-up strip 108 having at one end a roller 109 and to the other end a fixed jaw 135 and a movable jaw 110. Each pick-up strip (Figures 9 and 10) also has a bracket 111 furnished with an eye 112 through which a different weft supply is threaded. The jaw 110 is on a slide 113 slidable in the strip 108 having a notch 114 engaged by a finger 115 provided on one of the pivotal links 107. The slide 113 has an enlarged end 116. A compression spring 117 is provided between the strip 108 and the end 116 to close the movable jaw 110 by displacing the slide 113 in one direction axially and keep it closed until opened by the finger 115 displacing the slide 113 axially in the reverse direction. The leading end of a different supply of weft carried by a stationary part extends in a stretched state between the eye 112 and jaws 135 and 110 which grip the said end as the strip 108 arrives at the pick-up station 64. Each strip 108 arrives at the said station in turn as the foot 106 carrying the same arrives at the top of its rise. As the foot approaches the said top, a slide 118, see also Figures 11 and 12, slidably mounted on the foot 106 and having a stud 119 is prevented from rising due to obstruction of the stud 119 by the lower bracket 104. The slide 118 is connected by a pivotal link 120 to one of the links 107 and consequently the said link 107 is made to swing in clockwise direction and thereby advance the strip into the position in which the uppermost strip 108 is shown in Figure 3, and in which therefore the stretched weft is at the pick-up station. Whilst the strip is in that position, the jaws 65, 66 grip the leading end and convey it in the hereinbefore described manner to the giving position, whereupon the said end is gripped by two of the jaws 33, 37 and carried by the coiler 16 round the axis of the shaft 4. As the strip 108 nears its fully advanced position, the finger 115 operates the slide 113 to open the jaw 110 and thereby release the said leading weft end from the jaws 135 and 110, but not until the said end has been engaged and gripped by the jaws 65, 66.

As the coiler 16 descends in its revolution round the axis of the main shaft 4, the respective cam 100 causes the foot 106 to fall so that the strip 108 reaches its lowermost position, which is the position of the lowermost strip shown in Figure 3. Whilst the strip descends, it is kept in its advanced position by a spring-loaded catch 121 engaging a recess 122 in the foot 106. After the strip 108 has arrived at its lowermost position the said cam 100 causes the foot 106 to continue its fall, but the downward movement of the strip 108 is arrested by a stationary abutment 123 which supports the roller 109 of the strip. Consequently the links 107 are rotated in anticlockwise direction and the strip 108 is retracted, the catch 121 being forced out of the recess 122 and the slide 118 being pushed upwards until the stud projects above the foot 106 and the catch 121 engages a recess 124 and therefore yieldably locks the strip in the retracted position. The foot 106 thereupon is raised by its cam 100 and raises the

strip 108 whilst in the withdrawn position back to its initial uppermost position. Because the ascending strips 108 are in the withdrawn position whilst they are rising, they do not foul any of the descending strips 108. As each strip 108 is reaching its uppermost position it is advanced by stoppage of its stud 119 in the hereinbefore described manner. In Figure 3 the second lower strip shown is in the retracted position and in the act of rising.

Each coiler 16 acquires at the pick-up station the leading end of a different weft supply from a different strip 108. The weft runs through the eye 112 and is not severed until somewhat more than a sufficient amount of weft for one pick has passed through the eye, by which time the strip 108 has descended to its lowermost position and a deflector (not shown) has deflected the weft which is near the eye into a path where it again extends between the jaws 135 and 110 and the jaw 110 has gripped it, the weft being thereupon severed by a cutter (not shown) provided near the said jaws, and the severance forming a fresh leading end held ready to be taken by the jaws 65, 66 of another coiler 16 when the strip again arrives at the pick-up station 64. Because there are more strips than coilers, there is always a strip presenting a weft end at the pick-up station to every coiler 16 after the coiler has been relieved of its charge of coiled weft. Because the strips are arranged radially in plan view they are able to advance to the pick-up station in turn and recede without obstructing one another.

If different colours or kinds of weft are to be woven into the warp, each foot 106 has a series of feed strips separately hung on it side by side and controlled by a separate advancing mechanism and drawing its thread from a supply of weft thread of a different colour or kind and a selecting device is provided to advance by means of its advancing mechanism only that strip of each series which carries the particular kind or colour of weft thread required in the production of the desired fabric. Furthermore, if desired, two or more wefts, instead of the single weft hereinbefore referred to, may be supplied simultaneously by the strip and fed to and coiled simultaneously on the row of prongs 36 and be then simultaneously transferred to the shuttle 1.

The total length of weft coils wound on each coiler at each coiling is dependent on the diameter of the row of prongs 36. To adjust the said total length, the prongs 36 may be adapted to be adjusted towards and away from the axis of the said row, or the cams 12, 13 and 44 be changed for other cams whose lifts and falls are situated to initiate and stop the coiling at other appropriate moments. Conveniently and therefore preferably, the cams 12, 13 and 44 are adjustable for the purpose. For example, as shown in Figures 7 and 8, the lift 52 of the cam 13 may be on a separate adjustable arcuate horn 125 which is offset axially relative to the non-adjustable portion of the cam and is carried by a ring segment 126 which also carries an arcuate horn 127 forming an axially displaced continuation of the cam 12. The ring segment 126 also has arcuate horns 128 and 129 respectively, of which 128 has the lift 53 of the cam 44. The arcuate horns 128 and 129 form axially displaced continuations of the non-adjustable portion of the cam 44. The cam surfaces of the cams 12, 13 and 14 are continued across the face of the segment 126. A recess 130 is provided in which the segment 126 can slide. The segment 126 is shown in that position of ad-

justment which gives the maximum amount of coiled weft on each coiler. By angular displacement of the segment 126 in clockwise direction, the lifts 52 and 53 are displaced angularly in clockwise direction and therefore temporary stoppage of the main arm 15 by means of the lift 52 whilst the drive of the rows of prongs 36 is initiated by means of the lift 53 is delayed so that the coiling period or run of the coiler 16 is reduced. To hold the segment 126 in the adjusted position, it may have a spring catch 131 accommodated in a slot 132 in the stand 3 and adapted to be engaged with any of a plurality of spaced recesses 133 in order to retain the segment 126 in any one of a plurality of different positions of adjustment. The recesses 133 are so spaced that the said lifts can operate only when the sleeve 21 is in an angular position in which the lugs 24 register with the spaces between the lugs 28. This is possible because the sleeve is driven positively and the positions in which the lugs register with the gaps are substantially invariable.

It is to be understood that coiling and transfer apparatus according to the said invention can be employed not only in conjunction with the hereinbefore described circular weaving arrangement, but, with suitable changes in position or posture or suitable minor modifications in construction where necessary, can be employed in conjunction with circular weaving looms wherein the warp is cylindrical and circular weaving looms wherein the warp is divided into separate parts, and circular looms wherein a separate piece of weft threaded is inserted by a single shuttle or each shuttle at each passage through a one-part or divided warp, or circular looms wherein a single shuttle or each shuttle is furnished at each replenishment with sufficient weft thread to enable weft thread to be woven in during two or more passages of the shuttle through a one-part or divided warp.

In an alternative, the inner and outer control cams 12 and 13 and other appropriate parts may be modified so that the revolution of the row of prongs 36 about the axis of the main shaft 4 neither stops nor slows down during the feed of yarn from a strip 108 to the said row.

I claim:

1. A weft replenishing apparatus for circular looms, comprising shuttles travelling along a circular path in unidirection, weft coilers, means for constraining the weft coilers to follow a predetermined closed path at one part of which the weft coilers successively register substantially with the shuttles, means for driving the weft coilers at substantially the same speed as the shuttles whilst the weft coilers are registering substantially with the shuttles, and means for slipping weft coils from the coilers whilst the weft coilers are in register substantially with the shuttles and being driven at substantially the same speed as the shuttles.

2. A weft replenishing apparatus for replenishing the shuttles of circular looms with weft, comprising weft coilers which move along a circular path, means for moving the weft coilers along the circular path, said path at one part leading to weft coils into engagement with parts of the shuttles for providing opportunities for the transfer of weft coils from the weft coilers to the said parts of the shuttles.

3. A weft replenishing apparatus for replenishing the shuttles of circular looms with weft, comprising weft coilers which move along a closed path and at a point in the said path register

substantially with the shuttles, means for moving the weft coilers along the said path at a varying speed which is at a maximum whilst the weft coilers are at the said point, and a weft carrier provided on each shuttle, each weft coiler being immediately above one of the weft carriers at the point of registration for slipping weft coils downwards from the weft coiler on to a weft carrier whilst the coiler and shuttle are travelling along their paths.

4. A weft replenishing apparatus for replenishing the shuttles of circular looms with weft, comprising weft coilers which come periodically into register with the shuttles, and weft carriers on the shuttles, each weft carrier and coiler being in engagement one partly within the other at the moment at which weft coils are slipped from the weft coiler on to the weft carrier, for maintaining full control over the coils during the slipping operation.

5. A weft replenishing apparatus for replenishing the shuttles of circular looms with weft, comprising weft coilers, means for driving the weft coilers along a closed path, means for rotating each weft coiler about its axis whilst it is driven along its closed path, a shuttle path which leads each shuttle into a position of momentary registration with a weft coiler, the rotation of the weft coilers being for winding coils of weft on to the weft coilers for transfer to the shuttles.

6. A weft replenishing apparatus for replenishing the shuttles of circular looms with weft, comprising weft coilers driven along a closed path, mechanism for stopping the weft coilers in the closed path, means for feeding weft to the weft coilers whilst they are stopped, means for driving the weft coilers along the closed path at an increased speed during periods of transfer of weft from the weft coilers to the shuttles, and means for transferring weft coils from the weft coilers to the shuttles.

7. A weft replenishing apparatus for replenishing the shuttles of circular looms with weft, comprising weft coilers, means for driving the weft coilers along a closed path, means for rotating the weft coilers intermittently about their axes, holding means for holding the leading ends of supplies of weft in an accessible position, means for transferring the said leading ends from the holding means to the weft coilers, jaws on the weft coilers for gripping the leading ends and thereby temporarily attaching them to the weft coilers for coiling coils of weft on the weft coilers whilst they rotate about their axes, and means on the weft coilers for pushing the said coils of weft off the weft coilers whilst the weft coilers are in register with the shuttles.

8. A weft replenishing apparatus for replenishing the shuttles of circular looms with weft, comprising weft coilers, means for driving the weft coilers along a closed path, weft holding devices for temporarily and alternately holding pieces of weft by their leading ends, guiding the said pieces and holding the said pieces by their trailing ends, a mechanism on each weft coiler for gripping one of said leading ends and conveying said end to the weft coiler, a gripping mechanism on each weft coiler for gripping the conveyed leading end, means for rotating each weft coiler for coiling some of the piece on to itself in coils, and means for effecting a transference of the said coils from the weft coiler to one of the shuttles.

9. A weft replenishing apparatus for replenishing the shuttles of circular looms with weft, comprising a series of weft holding, presenting and

13

guiding mechanisms each for a weft from a different supply, coilers for coiling the presented wefts into coils, discharging means on the coilers for discharging the weft coils from the coilers on to the shuttles, the said mechanisms holding the weft until a portion thereof has been woven in by the loom.

10. A weft replenishing apparatus for replenishing the shuttles of circular looms with weft, comprising weft coilers, means for driving the weft coilers along a closed path which constrains each coiler in turn to register with a shuttle, a weft presenting mechanism which presents the leading end of weft, a swinging feed mechanism for taking the said leading end from the place of its presentation by the weft presenting mechanism and feeding the said leading end to the coiler, and a gripping device on the coiler for gripping the said leading end and thereby connecting it to the coiler.

11. A weft replenishing apparatus for replenishing the shuttles of circular looms with weft, wherein there are weft coilers driven along a closed path, an annular row of prongs provided on each coiler for winding weft into coils thereon, a pusher on each coiler for pushing coils of weft off the said row of prongs, and there is a carrier on each shuttle for receiving the coils of weft pushed off the said row of prongs.

12. A weft replenishing apparatus for replenishing the shuttles of circular looms with weft, comprising weft coilers, an annular row of adjustable prongs on each coiler for winding weft into coils on the said row, and means for adjusting the said prongs for changing the diameter of the said row and therefore the length of the coils wound on the said row.

13. A weft replenishing apparatus for replenishing the shuttles of a circular loom with weft, comprising coiling members, a circular path along which the coiling members are movable, means for driving the coiling members along the circular path, an annular row of coiling prongs provided on each coiling member and rotatable about its own axis, a driving member provided on each coiling member, a gear wheel connected to the driving member, a stationary annular row of teeth in constant mesh with the gear wheel, a pushing member for rotating the annular row of coiling prongs about its own axis and also for pushing weft coils off the said row, a slidable coupling member for coupling the driving member to the pusher and thereby causing the row of prongs to be rotated about its own axis and a stationary cam for operating the coupling member.

14. A weft replenishing apparatus for replenishing the shuttles of circular looms with weft, comprising a weft coiler movable along a circular path at one point of which the coiler can register with a shuttle, means for driving the weft coiler along the said path, an annular row of prongs forming part of the weft coiler and rotatable about its own axis, a driving and pushing member slidable on the coiler, a stationary annular toothed track, a gear wheel meshing with the said track, a locking part on the coiler which is not rotatable about the said axis, and means on the driving and pushing member for making in one position of the said member a driving connection between the gear wheel and the row of prongs and means on the driving and pushing member for making in another position of the said member a connection between the driving and pushing member and the locking part and

14

thereby locking the row of prongs against rotation.

15. A weft replenishing apparatus for replenishing the shuttles of circular looms with weft, comprising weft coilers separate from the shuttles but adapted to register with the shuttles at a predetermined place in the path of the shuttles, pairs of gripper jaws on each weft coiler for gripping the leading end of a weft supply, a movable part carrying the first jaw of each pair, spring means loading the said movable part, a pusher carrying the second jaw of each pair for pushing the second jaws against the first jaws and thereby gripping the said leading end whilst the pusher performs a stage of its pushing movement, and for separating the second jaws from the first jaws and thereby releasing the said leading end during a later stage of its pushing movement.

20 16. A weft replenishing apparatus for replenishing the shuttles of circular looms with weft, comprising a stationary cam, a coiler movable along a circular path at one part of which the coiler is in register with a shuttle, a pusher on the coiler, a coiler driving sleeve on the coiler, a lever driven along with the coiler and acted on by the stationary cam for disconnecting the pusher from the driving sleeve and thereby ceasing to rotate the coiler, and means for returning the lever to its initial position when the said cam ceases to act on the lever.

25 17. A weft replenishing apparatus for replenishing the shuttles of circular looms with weft, comprising a plurality of weft coilers movable along a circular path for coiling weft on to them, arms for driving the coilers along the said circular path, levers connecting said arms to a driving disc, driving means for rotating the weft coilers about their own axes, means for connecting and disconnecting the said driving means, a stationary cam for stopping the journey of each coiler round its circular path whilst the driving means are connected and a stationary cam for again stopping the journey of each coiler whilst the driving means are disconnected prior to the transfer of weft coils to a shuttle.

30 18. A weft replenishing apparatus for supplying weft to the shuttles of circular looms without stoppage of the said shuttles, comprising a plurality of intermittently revolving weft coiling devices which move into register with the shuttles for enabling weft coils to be deposited from the coilers on to the shuttles, driving mechanisms operated by the revolution of the coiling devices and rotating the coiler mechanisms intermittently about their own axes for winding weft on to the coilers, means for feeding weft to the coilers, cam means for varying the speed of revolution of the coilers, adjustable cam means for varying the periods of operation of the driving mechanisms which rotate the coiling mechanisms about their own axes and thereby varying the length of weft coiled on by the coiling mechanisms.

HENRY JAMES COOPER.
